PORTABLE SPACE HEATER

Everett L. Schofield and Grant E. Hatcher, Lee's Summit,
and Coy H. Hicks, Kansas City, Mo., assignors to Sam
Mulkey Company, Lee's Summit, Mo., a corporation of
Missouri

Filed June 22, 1964, Ser. No. 80,510

Term of patent 7 years

(Cl. D81—20)

Fig. 1.

Fig. 2.

Fig. 3.

Fig. 4.

Fig. 5.

FIG. 1 is a side elevational view of a portable space heater, showing our design, the other side being substantially a mirror image of that illustrated.

FIG. 2 is a perspective view of the portable space heater.

FIG. 3 is an elevational view of one end of the portable space heater.

FIG. 4 is an elevational view of the other end of the portable space heater.

FIG. 5 is a top plan view of the portable space heater. We claim:

The ornamental design for a portable space heater, as shown and described.
